CHRISTIAN AUGUSTUS ALBRECHT, OF BERLIN, GERMANY, ASSIGNOR TO MERGEN-THALER LINOTYPE COMPANY, OF BROOKLYN, NEW YORK, A COMPANY OF NEW YORK

MATRIX COMPOSING AND LINE CASTING MACHINE

Application filed September 11, 1931, Serial No. 562,207, and in Germany September 13, 1930.

In matrix composing and line casting machines, it has already been proposed, by the use of suitable moulds and matrices, to cast line-spacing material such as blank slugs, 5 low leads and the like. As such line-spacing material need not be produced with perfectly straight edges or side faces, it is not necessary to subject the cast slugs to the action of the trimming knives. On the other 10 hand, these blank slugs must be efficiently guided during their passage from the mould to the slug galley. It is therefore desirable in such cases to use the knife block as a guide by replacing one of the knives by a 15 spring-pressed guide plate or the like, which ensures the slugs travelling in the direction of their ejection. In arrangements of this character, as heretofore proposed, the springs occasionally fail to act and as a consequence thereof, the slugs assume an inclined position, and as the slugs are ejected by a thin blade, there is a danger of the blank slugs about to be ejected, becoming 20 jammed in the mould and causing damage 25 to the machine.

The present invention overcomes these difficulties by providing a guide whose width corresponds with the thickness of the blank slug then being cast, the said guide being 30 preferably controlled by the mould itself. For this purpose the mould is provided with a roller or a cam or the like which is adapted to bear against an abutment or projection connected with one of the guiding walls 35 or surfaces, and thereby adjust that wall relatively to the complementary wall, so that the distance between said walls will correspond with the width of the mould then in use.

40 In the accompanying drawing, one constructional form of the invention is illustrated and in this drawing:—

Figure 1 is a front elevation of the guiding mechanism;

45 Figure 2 a section on the line 2—2 of Figure 1, and

Figure 3 is a section on the line 3—3 of Figure 1.

50 The moulds *b*, as ordinarily are carried on the mould disc *a*. The trimming device

which comprises a stationary and an adjustable knife, is mounted in front of the mould on the vise frame *c*, of which latter only a fragment is illustrated. The stationary knife *d* is retained in the constructional 55 form according to the invention, but, on the other hand, the movable knife is replaced by an adjustable plate *e* whose position determines the width of the space through which the blank slugs issuing from the mould *b* have to pass. The knife *d* therefore, in conjunction with the plate *e*, forms the guide for the blank slugs. The plate *e* carries a blade or wing *f*, which is attached to the plate as by screws *g* and is movable 60 in a guide *h* on the vise frame *c*.

Springs *i* attached at one end to the blade *f* and at the other end to the guide *h* tend to move the blade, and with it the plate *e* towards the stationary knife *d*. This movement is limited by a plunger or bolt *n*, to which is attached a stud *o* and which is moved rearwardly in a socket *k* by a spring *p*, encircling the said stud, which latter is provided with a head to limit the movement 75 in that direction. A roller *q*, pivotally mounted on the bolt *n*, is adapted to travel over an edge cam or the like *r*, attached to the mould *b*.

The mode of operation of the device is as 80 follows:—

When the mould is not in ejecting position, the springs *i* hold the plate *e* as near to the stationary knife *d* as is permitted by 85 the slot *m*, against the left-hand of which (as viewed in Figures 1 and 2) the socket *k* is then in contact. When the mould *b* arrives at the ejecting position, the cam *r* engages with the roller *q* and thereby the blade 90 *f* with the plate *e* is moved outwardly against the action of the springs *i*, so that said plate will be adjusted at the correct distance from the fixed knife *d*, to enable it to act as a guide for the blank slug next 95 to be ejected.

The resilient mounting of the roller *q* on the blade *f*, is provided for the purpose of maintaining said roller in engagement with the cam *r* throughout the usual forward and 100

backward movement of the mould and mould carrier.

The before described arrangement can be modified without departing from the spirit 5 of the invention, for example, the roller can be mounted on the mould and adapted to engage a cam operatively fast to the plate *e*. The stationary side of the slug guide need not necessarily be constituted by the stationary 10 knife, for, in its place another guide wall or the like could be used. Likewise the cam *r* need not be mounted directly upon the mould *b*, but could for example also be arranged on the mould carrier *a*.

15 Having described my invention, I declare that what I claim and desire to secure by Letters Patent is:—

20 1. In a matrix composing and line casting machine, the combination with a casting mould adapted to cast blank slugs and the like, and of which one wall is movable for adjustment to effect the casting of slugs of different thickness, of a non-trimming slug guide through which pass the slugs ejected 25 from the mould, comprising two walls of which one is adjustable bodily relatively to the other to vary the distance between them to correspond with the distance between the mould walls.

30 2. In a matrix composing and line casting machine, the combination with a casting mould adapted to cast blank slugs and the like, and of which one wall is movable for adjustment to effect the casting of slugs of 35 different thickness, of a slug guide through which pass the slugs ejected from the mould, comprising two walls of which one is adjustable relatively to the other to vary the distance between them to correspond with the distance between the mould walls, springs tending to move the adjustable guide 40 wall in one direction, and co-operating cam and roller on the mould and adjustable guide wall, adapted to move the latter antagonistically to the springs.

45 3. In a matrix composing and line casting machine, the combination with a casting mould adapted to cast blank slugs and the like, and of which one wall is movable for adjustment to effect the casting of slugs of 50 different thickness, of a vise frame, a slug guide on said vise frame, through which pass the slugs ejected from the mould, comprising two walls of which one is adjustable 55 relatively both to the vise frame and to the other wall to vary the distance between said walls to correspond with the distance between the mould walls, springs anchored to the vise frame tending to move the adjustable guide wall in one direction, a guide on the vise frame for the adjustable guide wall, and co-operating cam and roller on the mould and adjustable guide wall adapted to move the latter antagonistically to the 60 springs.

4. In a matrix composing and line casting machine, the combination with a casting mould adapted to cast blank slugs and the like, and of which one wall is movable for adjustment to effect the casting of slugs of 65 different thickness, and which mould is movable from casting to ejecting position and when in ejecting position is moved also forwardly and backwardly, of a slug guide through which pass the slugs ejected from the mould, comprising two walls of which one is adjustable relatively to the other to vary the distance between them to correspond with the thickness of the cast slug, 70 springs tending to move the adjustable guide wall in one direction, co-operating cam and roller on the mould and adjustable guide wall, adapted to move the latter antagonistically to the springs, and means operative to maintain co-operation between the 75 cam rollers during the fore and aft movement of the mould.

5. Matrix composing and line casting machine, characterised by the fact that on the guide plate which takes the place of the adjustable knife when line spacing material or the like, is cast, is mounted a stop which is adapted to be engaged directly by a cam or the like preferably arranged on the adjustable section of the mould, that the guide 80 plate in the ejecting position of the mould, will be adjusted so as to correspond with the slug width.

6. Matrix composing and line casting machine, according to claim 5, characterised 85 by the fact that the stop (*g*) is movable inwards towards and outwards from the mould.

7. In a matrix composing and line casting machine, the combination with a casting mould adapted to cast blank slugs and the like, and of which one wall is movable for adjustment to effect the casting of slugs of different thickness, of a slug guide through which pass the slugs ejected from the mould, comprising two walls of which one is adjustable relatively to the other to vary the distance between them to correspond with the distance between the mould walls, means tending to move the adjustable guide wall in one direction, and means actuated by the movement of the mould from casting to ejecting position for moving the adjustable guide wall in the opposite direction.

8. In a matrix composing and line casting machine, the combination with a casting mould adapted to cast blank slugs and the like, and of which one wall is movable for adjustment to effect the casting of slugs of different thickness, of a slug guide through which pass the slugs ejected from the mould, comprising two walls of which one is adjustable relatively to the other to vary the distance between them to correspond with 120

the distance between the mould walls, means tending to move the adjustable guide wall in one direction, and cooperating means on the mould and adjustable guide wall 5 adapted to move the latter in the opposite direction as the mould is moved from casting position to ejecting position.

9. In a slug casting machine, the combination of a slotted mould adjustable to vary 10 the width of the mould slot, a rotatable mould carrier for moving the mould from casting to ejecting position, a slug guide through which slugs ejected from the mould pass, said guide being adjustable in width to 15 correspond with the width of the mould slot, and automatic means actuated by the rotation of the mould carrier for effecting such adjustment of the slug guide.

10. In a slug casting machine, the combination of a slotted mould adjustable to vary 20 the width of the mould slot, a rotatable mould carrier for moving the mould from casting to ejecting position, a slug guide through which slugs ejected from the mould pass, said guide having one wall adjustable 25 relatively to the other to vary the width of the guide in accordance with the width of the mould slot, a laterally movable support for the adjustable guide wall, and a pair of 30 elements, one carried by the mould wheel and the other by the guide wall support, adapted to be engaged by the rotation of the mould wheel for effecting the adjustment of the guide wall to correspond with 35 the width of the mould slot.

11. In a slug casting machine, the combination of a slotted mould having one of 40 its side walls adjustable toward and from the other to vary the width of the mould slot, a slug guide through which the slugs ejected from the mould pass, said guide also having one of its side walls adjustable toward and from the other to vary the width of the guide in accordance with that of the 45 mould slot, and a pair of elements, one carried by the adjustable mould wall and the other by the adjustable guide wall, adapted to be engaged with each other after each 50 slug casting operation to cause the adjustable mould wall to effect a corresponding adjustment of the adjustable guide wall.

In testimony whereof I have affixed my signature hereto.

CHRISTIAN AUGUSTUS ALBRECHT.
